REMOTE CONTROL SYSTEM

Lauritz E. Mylting, Hoboken, N. J.

Application September 1, 1928, Serial No. 303,434

4 Claims. (Cl. 177—351)

The invention relates to remote control systems embodying apparatus, for example, suitable as a long-distance water-level recording gauge. It has for its object a simple, rugged and effective 5 measuring or like system operating with precision to indicate or record conditions prevailing at a remote station; also to devise a system of this character which shall require a minimum of interconnecting circuits between stations.

10 In carrying out the invention, use is made of two or more synchronously operating devices, as synchronous motors which may be driven from a source of alternating electricity common to the various stations, such as a power line extending 15 therebetween. Provision may be made at one of the stations, to wit: the station at which some change in a physical or other condition occurs, for opening and closing during recurring cycles 20 of constant frequency or equal length of time 25 periods, a circuit connecting the various stations, the means afforded for this purpose embodying two contact elements, one being operated from the synchronous device at the particular station and the other variable in accordance with some 30 local condition. The physical or other local change to be transmitted is arranged to affect an open-circuit or closed-circuit interval of a period and thereby influence apparatus responsive to such change in the circuit conditions and located 35 at a different station where the effect may be suitably indicated or recorded, said responsive means being under further control of the synchronous device at that station.

As the apparatus at both stations are operating 35 continuously, it will be evident that any change in the connecting circuit will immediately be apparent at a receiving station or stations; and the system herein disclosed thus may give notice of any break, short-circuit or other abnormal condition.

40 A further object of the invention resides in the provision of means for giving visible notice, for example, if the respective synchronous devices should for any reason get out of step and thus introduce error in the transmitted record. To this end, an additional circuit opening and closing means is provided at the transmitting station and operates jointly with its said contact controlling means to open said circuit for a fixed 45 interval of each cycle and as determined by the synchronous device at the transmitting station.

50 The nature of the invention, however, will best be understood when described in connection with the accompanying drawing, in which:

Fig. 1 is a diagrammatic view illustrating the electrical connections between two stations.

Fig. 2 is a perspective view, more or less diagrammatic, illustrating apparatus suitable for use in the novel control system.

5 Referring to the drawing, more particularly Fig. 1 thereof, 10 designates one of a plurality of stations, for example, the station at which certain local conditions occurring are to be reproduced as by indicating or recording the same at one or 10 more remote stations, as the station 11. These stations have available a suitable source or sources of alternating current, for example, the power main 12 common to both stations. At each of the stations, moreover, is provided a synchronous 15 motor 13 and a synchronous motor 14, respectively, connected to the power main 12 and operated therefrom in synchronism.

The motor 13 at the transmitting station is 20 designed to have rotate continuously therewith contact means embodying the element 15, driven from the motor shaft 16 to rotate therewith, while a further element 17 cooperates with the element 15 to make and break a suitably energized 25 control circuit 18 connecting the two stations 10 25 and 11. The latter element may comprise, for example, a tank, as shown in Fig. 2, containing a conductive liquid such as mercury and into which the former element 15 is adapted to dip as it is rotated periodically and in recurring cycles 30 of equal time periods under the influence of its driving synchronous motor 13.

This rotatable contact-making element is 35 shown formed as a more or less heart-shaped member or cam; and is located with reference to the maximum level of the mercury element 17 so that, when the flattened portion thereof is substantially horizontal, contact between the two elements will be entirely broken. Once at least, therefore, during each cycle the circuit will be 40 broken at this point; and, moreover, the duration of the open-circuit interval will depend upon the level of the mercury in the tank.

In accordance with the invention, this level is 45 variable to correspond with the particular condition it is desired to transmit to the remote station 11, but should not fall below a level suitable to afford an appreciable contact period. Various physical changes or other causes may operate to alter this level, for example, pressure changes 50 may be transmitted thereto through a pipe 19, then also filled with mercury, and leading to a device of any well-known or special design (not shown) subject, for example, to the weight of a column of water. This device may thereby serve 55

as a means for transmitting to the remote station 11 the height of water in a reservoir (not shown) and located at the station 10.

To reproduce these conditions at the former station, the circuit 18 has included in series therewith, means responsive to the current flowing in said circuit, for example, the solenoid 20. The latter is adapted through its plunger to attract a platen frame 21 when said circuit is energized 10 and move said frame against the record strip 22, suitably advanced in any well-known or special manner, to force thereby the strip into contact with a recording pen 23 of a reciprocable pen carriage 24.

15 The latter is designed to be reciprocated across the strip 22 in cycles corresponding to the cycles of the contact means 15; and to this end a heart-shaped member 25, similar to the said member 15, is driven from the synchronous motor 14 at 20 the receiving station 11 and is designed to contact with a tangential spring-drawn bar 26 attached to the said carriage. The latter is guided for the reciprocating movement in a suitable guideway 27.

25 Thus, during each complete cycle of the contact means 15, the pen 23 will be drawn across the strip 22 and returned to the initial position, indicated in Fig. 2 of the drawing. At the particular interval that the circuit is closed at the 30 contact means, through engagement of the element 15 with the mercury 17, strip 22 will be pressed into contact with the pen 23 and a record 35 effected thereon.

35 The element 15, furthermore, is so designed that a predetermined angular movement thereof equals a definite vertical displacement of the contact range; and a definite variation in the level of the mercury 17 will be correspondingly reproduced by the pen 23. It will be understood 40 that the indication transmitted may be variously accomplished and that, also, the open-circuit interval rather than the closed-circuit interval may be utilized for this purpose, or various combinations thereof.

45 However, should the synchronous devices at the various stations for some reason get out of step, it will be appreciated that correct indications or records will not be afforded at the station 11. Provision has, therefore, been made to at once 50 afford an indication of such departure from synchronous operation so that correction may immediately be made in the operation of the motors.

To this end, a second circuit controlling means is included in the circuit 18 at station 10 and is 55 operated from the shaft 16 of the motor 13 thereat. This contact controlling means embodies a semi-circular element 35 adapted to periodically dip into a body of mercury 36 which, however, remains always at the same level so that there 60 is a fixed ratio of open-circuit interval to closed-circuit interval for each cycle in the rotation of this member. The lowermost position of the point of the contact element 15, also, is timed to the middle circuit breaking period of the element 35; and is so arranged, moreover, that the latter always interrupts the circuit for an appreciable period during the contact period of element 15. In other words, during broken circuit periods of the member 35, member 15 will always 65 afford an appreciable period of contact before and after the break introduced by member 35.

70 This will result in cutting off an initial portion of the record 30 at the middle of the contact period so that the same will always start,

for example, at a line beyond the zero line 37, as indicated. Should, however, the two motors get out of synchronism, the movement of the pen 23 over the strip 22 will be ahead of or behind the proper time of closed-circuit conditions in the circuit 18 and a displaced break or gap would occur in the record portion 38 shown, for example, at 39, so that no basis of comparison of the records is possible. This would thus indicate that the apparatus is not functioning 10 properly so that steps could be taken immediately to correct the same. It is to be understood that the checking interval normally starts and terminates on the line shown immediately below the zero line 37, thus at all times leaving the 15 space below this line clear during normal operation. Should any mark appear in this space, it is indicative of trouble; and any occurrence of the checking break above and below the aforesaid datum line will invariably cause the normally clear space on the paper to be marked. Moreover, the contact interval of the member 35 is never less than approximately twice the checking break.

25 I claim:

1. A remote control system, comprising synchronously and continuously operating driving means located at separated transmitting and receiving stations respectively, an electric control circuit between the stations, transmitting means located in said circuit at the transmitting station and including an element operated by the synchronous driving means at this station for controlling periodically the electric circuit to afford recurring cycles wherein both open and closed circuit intervals are afforded and an element responsive to a variable condition and cooperating with the first-named element to vary the length of one of the intervals afforded thereby, a second transmitting means in series with the first-named transmitting means and embodying a circuit controlling device operated by the transmitting station synchronous driving means to afford always a fixed ratio of open-circuit interval to closed-circuit interval, means at the receiving station responsive to current in the said controlling circuit and including a platen movable thereby, a recording stylus, means controlled by the synchronous driving means at said receiving station and including a member to reciprocate said stylus, and a movable record sheet adapted to be brought into contact with said stylus by the said platen when the responsive means at the receiving station is energized by the joint operation of the two said transmitting means, said stylus then reciprocating simultaneously over the record sheet to effect a record thereon from a fixed base line of said sheet to a point representative of the quantity being measured, failure of the record to begin at said line being indicative of lack of synchronism of the transmitter and receiver.

2. A remote control system, comprising synchronously and continuously operating driving means located at separated transmitting and receiving stations respectively, an electric control circuit between the stations, transmitting means located in said circuit at the transmitting station and including an element operated by the synchronous driving means at this station for controlling periodically the electric circuit to afford recurring cycles wherein both open and closed circuit intervals are afforded and an element responsive to a variable condition and cooperating with the first-named element to vary

- the length of one of the intervals afforded thereby, a second transmitting means in series with the first-named transmitting means and embodying a circuit controlling device operated by 5 the transmitting station synchronous driving means to afford always a fixed ratio of open-circuit interval to closed-circuit interval, means at the receiving station responsive to current in said controlling circuit and including a platen 10 movable thereby, a recording stylus, means controlled by the synchronous driving means at said receiving station and including a member to reciprocate said stylus, and a movable record sheet adapted to be brought into contact with said 15 stylus by the said platen when the responsive means at the receiving station is energized by the joint operation of the two said transmitting means, the said stylus then reciprocating simultaneously over the record sheet to effect a record thereon from a fixed base line of said sheet to a point representative of the quantity being measured, failure of the record to begin at said line being indicative of lack of synchronism of the transmitter and receiver.
4. A remote control system, comprising synchronously and continuously operating driving means located at separated transmitting and receiving stations respectively, an electric control circuit between the stations, transmitting means located in said circuit at the transmitting station and including an element operated by the 20 synchronous driving means at this station for controlling periodically the electric circuit to afford recurring cycles wherein both open and closed circuit intervals are afforded and an element responsive to a variable condition and co-operating with the first-named element to vary the length of one of the intervals afforded thereby, a second transmitting means in series with the first-named transmitting means and embodying a circuit controlling device operated by the 25 transmitting station synchronous driving means to afford always a fixed ratio of open-circuit interval to closed-circuit interval, an electrical recording device at the receiving station responsive to current in the said controlling 30 circuit and including a stylus, means controlled by the synchronous driving means at said receiving station and including a member to reciprocate said stylus, and a movable record sheet adapted to be brought into contact with said 35 stylus when the responsive means at the receiving station is energized by the joint operation of the two said transmitting means, said stylus then reciprocating simultaneously over the record sheet to effect a record thereon from a fixed base line of said sheet to a point representative of the quantity being measured, failure of the record to begin at said line being indicative of lack of synchronism of the transmitter and receiver.
3. A remote control system, comprising synchronously and continuously operating driving means located at separated transmitting and receiving stations respectively, an electric control circuit between the stations, transmitting means located in said circuit at the transmitting station and including an element operated by the synchronous driving means at this station for controlling periodically the electric circuit to afford recurring cycles wherein both open and closed circuit intervals are afforded and an element responsive to a variable condition and co-operating with the first-named element to vary the length of one of the intervals afforded thereby, a second transmitting means in series with the first-named transmitting means and embodying a circuit controlling device operated by the transmitting station synchronous driving means to afford always a fixed ratio of open-circuit interval to closed-circuit interval and predetermined with reference to the first-named transmitting means, means at the receiving station responsive to current in the said controlling circuit and including a platen movable thereby, a recording 40 stylus, means controlled by the synchronous driv-
